A. DIETSCHE

ENVELOPE

Filed Sept. 27, 1921

Inventor
Adolph Dietzsche
By his Attorney
Richard Guin

UNITED STATES PATENT OFFICE.

ADOLPH DIETSCHÉ, OF NEW YORK, N. Y., ASSIGNOR TO AMERICAN LITHOGRAPHIC COMPANY, OF NEW YORK, N. Y., A CORPORATION OF NEW YORK.

ENVELOPE.

Application filed September 27, 1921. Serial No. 503,607.

To all whom it may concern:

Be it known that I, ADOLPH DIETSCHÉ, a citizen of the United States, and resident of New York, in the county of New York and 5 State of New York, have invented certain new and useful Improvements in Envelopes, of which the following is a specification.

This invention relates to an improvement in envelopes, having particular reference to 10 a multiple pocket envelope.

This invention has for an object to provide an inexpensive and easily constructed envelope presenting a plurality of pockets arranged to facilitate withdrawal of the 15 articles therefrom.

For further comprehension of the invention, and of the objects and advantages thereof, reference will be had to the following description and accompanying drawings, and to the appended claims in which the various novel features of the invention 20 are more particularly set forth.

Fig. 1 of the drawings is a face view of the blank from which the envelope is 25 formed.

Fig. 2 is a perspective view of the completed envelope.

Fig. 3 is a diagrammatic front edge view.

30 Fig. 4 is a longitudinal vertical sectional view taken along the plane indicated by the line 4—4 on Fig. 3.

Fig. 5 is a transverse vertical section taken on the plane indicated by the line 5—5 on 35 Fig. 3, but omitting the left hand pocket forming elements.

In constructing my improved envelope I form a blank such as shown in Fig. 1 and comprising a main central portion A at 40 the side of which are semi-circular pocket forming elements B. The body A has a flap extension 10 at its top. The body A is adapted to be folded along the horizontal dotted line *a* to produce the front 11 and back 12 of the envelope, the flap 10 being folded along the horizontal dotted line *b*. The fold line *a* is located approximately midway between upper and lower ends of the blank body A, the back portion 12 which 45 carries the flap 10 being, however, preferably slightly longer than the front portion 50

11 for convenience in folding the flap to close the envelope.

To form the pockets of the envelope the semi-circular side members B are each folded 55 as a whole along the sides, indicated by the dotted lines *c*, of the body A and are also folded along the lines *d* radiating from the ends of the fold line *a* of the body A to produce a plurality of pleat-like members 14 60 which fold in between the front 11 and back 12 as shown, these members 14 being of substantially triangular shape, with the bases of the triangles formed by the sides of the envelope, the parts being preferably 65 so proportioned that the inner pointed ends of the members on opposite sides of the envelope overlap each other. As is clearly shown in Figs. 2 and 3, these pleat-like members 14 divide the envelope into a series of 70 pockets, while it will also be apparent that these pockets may be readily opened out for inspection or withdrawal of the contents by swinging the front member 11 outwardly from the back member 12. To 75 fasten the envelope in closed position the flap 10 has a tab 15 formed thereon which may be inserted into a slot 16 in the front 11, although other fastening means may be provided if desired. It will be noted also 80 that the construction of the members B is such that when folded, the top edges of the pockets incline inwardly and downwardly from opposite sides of the envelope, facilitating grasping of articles inserted in 85 the pocket.

The envelope may be used for any desired purpose being particularly suitable as a carrier for hair nets, when sold in lots.

Having thus described my invention what 90 I claim as new and desire to protect by Letters Patent of the United States is as follows:

A blank adapted to be folded to form an hair net envelope having a plurality of 95 pockets therein, said blank consisting of a central main section provided with a folding line to form the front and back panels of said envelope, a pair of semi-circular side sections projecting laterally from said main 100 section, said side sections being provided with a plurality of folding lines radiating

from the ends of the folding line of said main section, and a portion of said side sections being cut out adjacent the meeting points of said lines to permit said side sections to be folded within said front and back panels to form a plurality of overlapping members, which divide the folded envelope into a plurality of pockets and the top edges of

which members extend downwardly in a curve from the tops of said panels toward the bottom thereof.

Signed at New York in the county of New York and State of New York this 30 day of Aug. A. D. 1921.

ADOLPH DIETSCHE.
